United States Patent Office

Des. 212,068
Patented Aug. 20, 1968

212,068

VANITY CASE OR SIMILAR ARTICLE

Mary K. Ash, 3523 Northwest Parkway,
Dallas, Tex. 75225

Filed Oct. 20, 1967, Ser. No. 9,080

Term of patent 14 years

(Cl. D86—10)

Fig.1

Fig.2

Fig.4

Fig.3

Fig.5

Fig.6

FIGURE 1 is a front perspective view of a vanity case or similar article showing my new design as it appears in a closed position;

FIGURE 6 is a top plan view thereof in an opened flat position, the broken line showing of brushes being for purposes of illustration only.

I claim:

The ornamental design for a vanity case or similar article, substantially as shown and described.
